CLAIM

The ornamental design for a controller for digital audio player, as shown and described.

DESCRIPTION

FIG. 1 is a top-right-front perspective view showing the controller for digital audio player of our design; FIG. 2 is a bottom-left-back perspective view thereof; FIG. 3 is a front view thereof; FIG. 4 is a rear view thereof; FIG. 5 is a top view thereof; FIG. 6 is a left-side view thereof; FIG. 7 is an enlarged partial view of an area indicated by lines 7-7 of FIG. 1, and shows details of the design not amenable for depiction in the view of FIG. 1; and, FIG. 8 is an enlarged partial view of an area indicated by lines 8-8 of FIG. 6, and shows details of the design not amenable for depiction in the view of FIG. 6. The broken lines depict portions of the controller for digital audio player that form no part of the claimed design. The dot-dash broken line rectangles depict the limits of the enlarged views and form no part of the claimed design.
